MERCURY CATHODE TUBE

Tom Jurriaanse, Eindhoven, Netherlands, assignor to N. V. Philips' Gloeilampenfabrieken, Eindhoven, Netherlands

Application February 15, 1937, Serial No. 125,943
In Germany February 17, 1936

5 Claims. (Cl. 250—27.5)

My invention relates to mercury-cathode tubes, such as mercury arc rectifiers and relays, and more particularly to the anchoring of the cathode spot of such tubes.

5 To stabilize the operation of such tubes, anchoring members are used to prevent the cathode spot from wandering over the surface of mercury and to prevent splashing of the mercury. If the portion of the envelope in the vicinity of the 10 cathode is of metal, or of glass coated with a conductive deposit such as mercury, such members prevent the cathode spot from passing over the surface of the mercury and reaching the conductive wall portion. This greatly reduces 15 the possibility of damage to the envelope, and especially to the metal-glass seal of envelopes having a metal portion and a glass portion fused together.

As the cathode spot generally settles at the 20 line of separation between the anchoring member and the mercury, i. e. at the cathode line, the surface at this point must be of perfectly pure metal free from oxides to ensure proper anchoring action. This condition can be satisfied 25 in a simple manner by making the anchoring member of a metal capable of amalgamating with mercury, as this amalgamation removes the surface layer and its impurities. However, metals which amalgamate sufficiently with mercury, for 30 instance copper, dissolve so rapidly in mercury—especially at the physically highly-stressed point at which the cathode spot settles—that the life of the member is reduced to such extent that the tube is soon rendered unserviceable.

35 If, to ensure a satisfactory life, the anchoring member is made of a material which is substantially insoluble in mercury, the anchoring properties are either very poor, or can be developed only with great difficulty. Thus, a completely 40 satisfactory solution of this problem in a simple manner was hitherto impossible, and a sufficient life of such members and of the tubes could be ensured only by using extremely pure and expensive metals such as platinum, or by resorting to 45 extremely complicated purifying methods during the manufacture of the tube.

The object of my invention is to overcome the above difficulties and to produce an anchoring member which has a long life and satisfactory 50 anchoring properties.

According to the invention, I form the anchoring member from a metal or a metal-alloy whose "dissolving speed in mercury" during the passage of discharge current is less than about $\frac{1}{10}$, prefer- 55 ably about 1/40, of that of copper, and which

amalgamates better than does iron or molybdenum.

The term "dissolving speed in mercury" as used herein and in the claims, is to be understood to mean the loss in material of the anchoring member due, inter alia, to amalgamation with the mercury and to disintegration by the discharge, per unit of time and per unit of arc current during the operation of the tube. 5

Anchoring members of such materials have 10 sufficiently long life for all practical purposes, and the settling point of the cathode spot upon the anchoring member is formed with full security and without taking additional measures, so that the manufacture of the tube is not complicated. Furthermore, the materials used are 15 standard and can be obtained at a comparatively low cost.

As the dissolving process and any corrosion phenomena at the settling point of the cathode 20 spot depend to a large extent upon the temperature, it is essential to have a good dissipation of heat from this point. For this purpose I prefer to locate the anchoring member in the middle 25 of the mercury cathode, and in good heat-transferring relationship with the envelope.

In order that my invention may be clearly understood and readily carried into effect, I shall describe same more fully with reference to the accompanying drawing, in which: 30

Figure 1 is a sectional side-view of a mercury-vapor rectifier embodying the invention;

Fig. 2 is a sectional view of an anchoring member according to the invention.

The rectifier shown in Figure 1 comprises an 35 envelope consisting of a cup-shaped metal member 1, for instance of chrome iron, and a glass member 2 hermetically fused together at 17. Disposed in the bottom of member 1 is a mercury cathode 3, whereas a main anode 8 is supported 40 from the lower end of a conductor 6 whose upper end is secured to a metal disc 4 hermetically sealed in glass portion 2 and carrying a terminal. Supported from conductor 6 and surrounding anode 8 is a cylindrical screen 11 serving to 45 protect the higher internal surfaces of portion 1 and seal 17 from the detrimental effects of the discharge.

Supported by screen 11, preferably of sheet molybdenum, is an insulating tube 20 through 50 the bore of which extends a conductive rod 19 carrying on its lower end an auxiliary anode 9. The anode 9 is adapted to be moved in the direction of the double-headed arrow, and for this purpose the upper end of rod 19 carries a plunger 55

18 of magnetic material electrically connected through a compression spring 22 to a core 21 of a magnetic material. Core 21 is supported from the lower end of a conductive rod 7 secured to a disc 5 hermetically sealed in glass portion 2. Outside the envelope and surrounding core 21 is coil 10 which serves to raise anode 9 from the surface of the mercury.

Surrounding metal member 1 is a cooling jacket 12 having an inlet opening 13 and an outlet opening 14, and through which a circulating cooling medium, such as water, is circulated in the direction of the arrows during operation of the rectifier. Jacket 13 is secured to metal member 1 by 15 a copper bolt 15 secured, for instance, by welding to the bottom of member 1 and serving to supply current to cathode 3.

Centrally disposed in the mercury cathode 3 is an anchoring member 16. According to the 20 invention, I form member 16 of a metal or metal alloy whose "dissolving speed in mercury" during the discharge of the discharge current is at the utmost $\frac{1}{6}$, and preferably about $1/40$, of that of copper, and which amalgamates better 25 than does iron or molybdenum. As a suitable material for this purpose I prefer to use nickel or an alloy substantially constituted by this metal.

To insure good dissipation of heat from member 16, the entire lower surface thereof is in direct metallic contact with the bottom of the member 1, and for instance, welded thereto. The member 15, which is of large size and of a good 30 heat-transmitting material, such as copper, is secured, for instance welded, to the lower surface of member 1 and thus aids in the dissipation of heat from the anchoring member 16.

As shown in Figure 1, member 16 is shaped as a disc; however it may be given various other 40 shapes, for instance as a ring 23, as shown in Fig. 2. The cathode line inside a ring shaped member, in contradistinction to that around a disc shaped member, will show a tendency to grow longer as a result of the gradual erosion of the member so that its current carrying capacity 45 is not impaired with the increase of the age of the tube. Furthermore, member 16 may have a rounded or roughened upper surface, and it is sometimes of advantage to use a porous structure.

50 While I have described my invention in connection with specific examples and applications, I do not wish to be limited thereto but desire

the appended claims to be construed as broadly as permissible in view of the prior art.

What I claim is:—

1. A mercury-cathode tube comprising an envelope having a wall portion of mercury-resistant metal forming part of the bottom thereof, electrodes within said envelope including a mercury cathode within the bottom part, and a massive cathode-spot anchoring member partly within said mercury cathode and carried by said metal wall portion, said member consisting of a metallic material substantially of nickel. 5

2. A mercury-cathode tube comprising an envelope having a wall portion of mercury-resistant metal forming part of the bottom thereof, electrodes within said envelope including a mercury cathode within the bottom part, and a massive cathode-spot anchoring member of nickel partly within said mercury cathode and carried by said metal wall portion. 10

20 3. A mercury-cathode tube comprising an envelope having a wall portion of mercury-resistant metal forming part of the bottom thereof, electrodes within said envelope including a mercury cathode within the bottom part, and a massive cathode-spot anchoring member partly within said mercury cathode and secured to said metal wall portion in good heat-transferring relationship, said member consisting of a metallic material substantially of nickel. 25

30 4. A mercury-cathode tube comprising an envelope having a wall portion of mercury-resistant metal forming part of the bottom thereof, means for artificially cooling said metal wall portion, electrodes within said envelope including a mercury cathode within the bottom part, and a massive cathode-spot anchoring member partly within said mercury cathode and secured to said wall portion in good heat-transferring relationship, said member consisting of a metallic material 35

40 45 5. A mercury-cathode tube comprising an envelope having a wall portion of mercury-resistant metal forming part of the bottom thereof, electrodes within said envelope including a mercury cathode within the bottom part, and a massive cathode-spot anchoring member partly within said mercury cathode and carried by said metal wall portion, said member having an annular shape and consisting of a metallic material substantially of nickel. 50

TOM JURRIAANSE.
